UNITED STATES PATENT OFFICE.

SAMUEL R. SHETZLINE, JR., OF PHILADELPHIA, PENNSYLVANIA, AND EMIL A. DODELIN, OF MOORESTOWN, NEW JERSEY.

SHOE-LACE FASTENER.

Application filed June 12, 1926. Serial No. 115,466.

Our invention relates to new and useful improvements in a shoe lace fastener, and has for its primary object to provide an exceedingly simple and effective device of 5 this character, which will be inexpensive in the cost of manufacture, easily applied to a shoe and efficient in operation.

Another object of the invention is to provide a shoe lace fastener adapted to receive 10 the straight and looped ends of a bow knot and hold such ends in a neat manner, thereby giving a tidy appearance to the footwear.

A further object of the invention is to produce such a fastener from a single piece 15 of wire, so bent as to provide a shoe engaging hook and a lace engaging hook, said hooks being arranged in opposed relation.

A still further object of the invention is to provide means for furnishing a large bearing 20 surface to the shoe engaging hook to prevent turning or tilting of the fastener.

With these and other ends in view, this invention consists in the details of construction and combination of elements herein- 25 after set forth and then specifically designated by the claim.

In order that those skilled in the art to 30 which this invention appertains, may understand how to make and use the same, we will describe its construction in detail, referring by numerals to the accompanying drawings forming a part of this application, in which:

Fig. 1, is a fragmentary perspective view 35 of a shoe, illustrating an application of our invention.

Fig. 2, is a side elevation of a shoe lace fastener embodying our invention.

Fig. 3, is a front elevation thereof.

In carrying out our invention as herein 40 embodied, 8 represents a shoe or article of footwear which is closed by laces 9, the upper ends of which are usually tied in a bowknot indicated at 10, and providing loop ends 11 and straight or tipped ends 12.

Usually the ends of the bowknot are 45 allowed to hang loosely, giving an untidy appearance to the footwear, but by providing a simple means to hold these loose ends, it would give a neat appearance to the shoe, and we accomplish this by forming a shoe lace fastener 13 from a single piece of wire 50 so bent or fashioned as to provide a loop 14 at one end, and then bend the wire upon itself, intermediate its ends to form a prong

15 and a body 16, the said wire being again bent upon itself in the opposite direction so as to form a second or outer prong 17, said prongs being in alignment or directly behind each other at right angles to the 60 plane of the loop 14, and the terminus of the prong 17 is then bent upon itself as at 18 to provide a smooth or finished nose 19. The outer prong 17 may substantially parallel the body 16, but the inner prong 15 is 65 preferably bent outward intermediate its ends, as at 20, so that its lower end will lie in close proximity to the body and thus provide an efficient grip on the upper of the article of footwear to which it is attached. 70

By placing one of the shoe lace fasteners at each side of the front of the shoe, or in any other convenient place, relative to shoe laces, the ends of the latter may be readily inserted between the outer prong 17 and the 75 body 16, where they will be held against accidental displacement due to the resiliency of the fastener. In placing the fasteners in position, the inner hook 15 engages the inner 80 face of the shoe upper, while the body engages the outer face thereof, and by providing the loop 14 of extended area, regardless of its shape, it will have considerable bearing on the inner face of the shoe, and therefore the fastener cannot turn or swing 85 from side to side.

Of course we do not wish to be limited to the exact details of construction as herein shown as these may be varied within the limits of the appended claim without departing from the spirit of our invention. 90

Having thus fully described our invention, what we claim as new and useful is:

A shoe lace fastener produced from a single piece of wire having one end fastened into a loop to provide an extended bearing surface, said wire being bent upon itself intermediate its length to provide an inner hook supporting said loop and a body, and further bent upon itself in the opposite 95 direction to provide an outer hook, the end of which is bent back upon itself so as to form a finished nose, and said inner hook being bent outward intermediate its ends so that the loop portion projects in close 100 proximity to the body.

In testimony whereof, we have hereunto affixed our signatures.

EMIL A. DODELIN.
